INVENTOR

Franklin Webster,
BY A. M. Pierce,
ATTORNEY.

UNITED STATES PATENT OFFICE.

FRANKLIN WEBSTER, OF EAST ORANGE, NEW JERSEY.

DESIGN FOR A BLOTTER-HOLDING RULER.

SPECIFICATION forming part of Design No. 33,944, dated January 22, 1901.

Application filed December 22, 1900. Serial No. 40,822. Term of patent 7 years.

To all whom it may concern:

Be it known that I, FRANKLIN WEBSTER, a citizen of the United States, residing at East Orange, in the county of Essex and State of New Jersey, have invented and produced a new and original Design for Blotter-Holding Rulers, of which the following is a specification.

In the accompanying drawings, forming a part hereof, Figure 1 is a plan view, and Fig. 2 an end elevation, of a ruler, showing my design.

Similar numerals of reference wherever they occur indicate corresponding parts in both figures.

The structure is formed of a single piece of

sheet metal having a straight base or lower lip 1, from which the metal curves backward and upward, constituting a partial cylinder 2, the material terminating in a curved portion or upper lip 3 over the lower lip 1.

Having described my invention, what I claim, and desire to secure by Letters Patent, is—

The design for a blotter-holding ruler, substantially as herein shown and described.

Signed by me at New York, N. Y., this 20th day of December, 1900.

FRANKLIN WEBSTER.
